FLAMELESS TORCH FOR HEATING, DRYING AND MELTING PLASTICS AND THE LIKE

Richard W. Henes, Phoenix, and Frithiof F. Nielsen,
Tempe, Ariz., assignors to Henes Manufacturing Com-
pany, Inc., Phoenix, Ariz.

Filed July 8, 1965, Ser. No. 86,065

Term of patent 14 years

(Cl. D62—2)

FIG. 1 is a front perspective view of a flameless torch for heating, drying and melting plastics and the like; and

FIG. 2 is a back perspective view of FIG. 1.

The flexible hose shown by broken lines in FIGS. 1 and 2 connects the device to a source of gas and is for illustrative purposes only.

We claim:

The ornamental design for a flameless torch for heating, drying and melting plastics and the like, as shown and described.
